United States Patent Office.

JACOB SCOTT, OF EARLVILLE, IOWA.

Letters Patent No. 98,422, dated December 28, 1869.

IMPROVEMENT IN PUMPS.

The Schedule referred to in these Letters Patent and making part of the same.

To all whom it may concern:

Be it known that I, JACOB SCOTT, of Earlville, county of Delaware, State of Iowa, have invented a new and improved Pump; and I do hereby declare that the following is a full, clear, and exact description thereof, reference being had to the accompanying drawings, and to the letters of reference marked thereon.

Figure 1 is a central vertical section, partly in elevation, of my improved pump, showing the position of the parts.

Figure 2 is a front elevation, showing how the exterior portions of the pump are held in position.

Corresponding letters refer to corresponding parts in each of the figures.

This invention relates to pumps for elevating water out of wells, or other reservoirs, and its object is to provide a pump less expensive in its construction, the parts of which are more simple, and easily constructed by persons not supplied with full sets of tools for pump-making, than are the pumps now in use; and to this end,

The invention consists in the construction and arrangement of the parts of which it is composed, as will be more fully described hereinafter.

A, in the drawings, is a closed box, of any required size, to be placed in or near the bottom of the well, or other reservoir containing the water to be raised. This box is to be provided with a series of apertures upon its sides for the admission of water to the interior thereof.

B represents a short cylinder, which is to be firmly secured to the upper surface of box A. This cylinder may be of any desired shape upon its outer surface, it being intended to use wood generally in its construction. It may, however, be of metal, or of any other material, it being provided with an aperture through its centre, within which the piston is to work. This aperture is to be placed directly over a corresponding aperture in the top of box A, so that a direct communication may be formed between the two.

C represents a valve, which is to be placed at the junction of the cylinder B with the box A, and so arranged that its seat shall be upon the box A, it opening upward into the aperture in cylinder B.

B' represents another and a shorter cylinder or tube, which is arranged vertically by the side of cylinder B, with which it communicates through an aperture formed in the side of the latter, at a point, say, three inches from its bottom or lower end.

C' represents a valve, which is hinged to, and has its seat upon the cylinder B, it being so arranged as to cover the aperture in its side which forms the communication. The office of this valve is to pre-

vent the water, after it has been forced out of cylinder B, by the downward motion of the piston, from returning thereto, as said piston is raised to allow the said cylinder to be refilled with water.

D represents the aperture above alluded to, which forms the communication between the cylinders B and B'.

E represents a piston, which fits the bore of the cylinder B, and may be of any length desired.

E¹ represents a rod, which is to be secured to the piston E, and extend upward above the top of the cylinder for a distance sufficient to enable it to be attached to the operating-handle.

E² represents the handle by which the piston of the pump is operated, its outer end being attached to a bracket, or standard, G, which is secured to the upper end of the cylinder B, as shown in fig. 1 in the drawings, or it may be attached to a standard at the top of the well, said standard being constructed independently of the cylinder B. To this handle the rod E¹ is attached, at a point directly over the aperture in cylinder B, so that as its outer or free end is moved up and down, water will be forced out of the said cylinder by the piston E, upon its downward stroke, the vacuum formed therein by its upward stroke, which will permit the water to flow in through valve G, and refill the same, so that the operation may be repeated.

F represents the discharge pipe of the pump, which is to be attached to the upper end of cylinder B', as shown in fig. 1, it leading from that point to the top of the well, and from thence to any point to which it may be desired to conduct the water.

At any point above the platform, covering the well or reservoir in which the water is contained, this discharge-pipe may be provided with a cap, having upon it the necessary screw for attaching a hose, which will cause the pump, when operated briskly, to perform the function of a fire-engine or a fire-extinguisher, and thus a safeguard against the destruction of buildings from that cause may always be at hand.

H H represent bolts, which are to be secured to the top of box A in any suitable manner, and extend up and through a cap of iron or other material, to be placed over the top of cylinder B.

Upon the outer upper ends of these bolts, nuts are to be placed, which will bear upon the cap I, and, as they are turned down, will press upon the cylinder B and box A, and thus unite the parts together, and prevent any leakage at the joints, they having been provided with suitable packing for that purpose.

Some of the advantages due to this form of construction may be stated as follows:

First, it is more simple, consequently less expensive than any other pump with which I am acquainted.

Second, it is easily and quickly convertible into an engine for extinguishing fires, which is regarded as a very important feature.

Having thus described my invention,

What I claim, and desire to secure by Letters Patent of the United States, is—

A pump, consisting of the perforated chamber A, the pump-stock B, eduction-pipe B', hinged valves C and C', eduction-passage D, solid piston E, piston-rod

E', lever E'', and fulcrum G, all as shown and described.

Signed at Earlville, Iowa, this 16th day of October, A. D. 1869.

JACOB SCOTT.
